(57)

CLAIM

The ornamental design for a modular vehicular roof rack, as shown and described.

DESCRIPTION

FIG. 1 illustrates a left-angled perspective view of the modular vehicular roof rack installed on a vehicle;
FIG. 2 illustrates a top view thereof;
FIG. 3 illustrates a front view thereof; and,
FIG. 4 illustrates a side view thereof.
In the drawings, the broken lines depict environmental subject matter only and form no part of the claimed design.
